ROBERT M. EVANS, OF SEATTLE, WASHINGTON.

METHOD OF MAKING ANDIRONS.

Application filed May 19, 1928. Serial No. 279,026.

This invention relates to andirons, and more particularly to a novel process or method of making andirons from short sections of railway rails; the principal object 5 of the invention being to provide andirons by a certain process or method of manufacture, whereby ornamental as well as efficient, useful and inexpensive articles are produced.

More specifically stated, the invention resides in the construction of andirons from short pieces of railway rails of that type now generally in use for all railroads, which consists of cutting out a portion of the web 10 at one end of the piece of rail, then splitting the base portion longitudinally along the line where the web has been removed, then turning the separated base portions outwardly to provide lateral supports and drawing out and shaping the ball portion of the rail above the cut out web to provide an ornamental retaining prong.

In accomplishing the objects of the invention, I have provided the improved details 5 of construction, as illustrated in the accompanying drawings, wherein—

Figure 1 is a perspective view of an andiron made in accordance with details of the present invention.

Figure 2 is a perspective view of a short piece of rail from which an andiron is to be made.

Figure 3 is a perspective view, showing the piece of rail with the web portion cut away at one end and the base portion split preparatory to forming the andiron.

Referring more in detail to the drawings—

1 designates an andiron made in accordance with details of the present invention; this being formed from a short piece of railway rail comprising the usual horizontal base flange 2 and ball portion 3 joined to the base by the central, longitudinally extending web 4. The method employed in forming the andiron is as follows: First, a

portion of the web 4 at one end of the piece is cut away so as to leave the base and ball portions projecting, as shown in Figure 2. The base is then split longitudinally, as indicated at 7, along the line where the web 50 has been removed. The separated pieces 2^a and 2^b of the base are then bent outwardly to provide lateral supports to prevent the andiron tipping. These may be drawn apart 55 so as to lie in the same plane as the base, or they may be curved backwardly and outwardly as shown in Figure 1, so that their end portions terminate in the plane of the base. The projecting portion of the ball of the rail, where the web has been removed, 60 is then drawn out by heating and hammering to a desired length and is curved upwardly and backwardly and may be then turned outwardly and downwardly to form an ornamental prong 10. This prong may 65 assume various shapes as is desired.

This process provides an easy and relatively inexpensive way of forming andirons from short rail sections which cannot be used for railway purposes, and it is readily apparent that the process may be followed in forming various other designs than that herein illustrated.

Having thus described my invention, what I claim as new is:

1. The process of forming andirons from short sections of railway rails, which consists of cutting away a portion of the web of the rail at one end of the piece and drawing out the extending ball portion and curving it upwardly to form a retaining prong.

2. The process of making andirons from short sections of railway rails which consists of cutting away a portion of the web of the rail at one end, splitting the base longitudinally along the line where the web is removed, turning the split portions of the base laterally to form lateral supports and forming the ball portion upwardly to serve as a retainer.

3. The process of forming andirons from short sections of railway rails, which consists of cutting away the web portion at one end of the piece, splitting the base portion along the line where the web is removed, turning the portions of the split base backwardly and outwardly to serve as lateral supports, drawing out the ball portion of the rail from which the web is removed and curving it upwardly to form a retaining prong.

Signed at Seattle, Washington, this 30th day of March, 1928.

ROBERT M. EVANS.
